FEMORAL HIP PROSTHESIS

Harlan C. Amstutz, 433 Burlingame Ave.,
Los Angeles, Calif.

Filed June 7, 1973, Ser. No. 368,414

Term of patent 14 years

Int. Cl. D24—03

U.S. CL. D83—1 E

FIG. 1 is a side elevational view of a first embodiment of a femoral hip prosthesis;

FIG. 2 is an end elevational view thereof;

FIG. 3 is a partial top plan view thereof taken along lines 3—3 of FIG. 1;

FIG. 4 is a sectional view thereof taken along lines 4—4 of FIG. 1;

FIG. 5 is a sectional view thereof taken along lines 5—5 of FIG. 1;

FIG. 6 is a sectional view thereof taken along lines 6—6 of FIG. 1;

FIG. 7 is a sectional view thereof taken along lines 7—7 of FIG. 1;

FIG. 8 is a fragmentary side elevational view of another embodiment of a femoral hip prosthesis;

FIG. 9 is a sectional view thereof taken along lines 9—9 of FIG. 8; and

FIG. 10 is a sectional view thereof taken along lines 10—10 of FIG. 8.

I claim:

The ornamental design for a femoral hip prosthesis, as shown and described.
